UNITED STATES PATENT OFFICE

163,039

TOY TYPEWRITER

Henry C. Hertz, Jackson, Mich., assignor to The
Dial-Writer Company, a partnership

Application September 15, 1949, Serial No. 5,009

Term of patent 7 years

(Cl. D34—15)

To all whom it may concern:

Be it known, that I, Henry C. Hertz, a citizen of the United States and a resident of Jackson, Jackson County, Michigan, have invented a new, original, and ornamental Design for a Toy Type-writer, of which the following is a specification, reference being had to the accompanying drawing, forming a part thereof.

In the drawing:

Figure 1 is a top front perspective view of the toy typewriter, showing my new design;

Figure 2 is a side elevation of the toy typewriter;

Figure 3 is a rear end elevation of the toy typewriter; and

Figure 4 is a side elevation of the toy typewriter showing the side opposite to that shown on Figure 2.

I claim:

The ornamental design for a toy typewriter, as shown.

HENRY C. HERTZ.
